Primary Examiner—Bernard Ansher*Assistant Examiner*—Dominic Simone*Attorney, Agent, or Firm*—Lahive & Cockfield[57] **CLAIM**

The ornamental design for a partitioned insert for cartons, as shown and described.

DESCRIPTION

FIG. 1 is a right side elevational view of a partitioned insert for cartons showing my new design;

FIG. 2 is a top plan view thereof, the bottom being identical;

FIG. 3 is a left side elevational view thereof;

FIG. 4 is a front elevational view thereof, the rear being identical;

FIG. 5 is a front elevational view thereof, in a position for storage; and,

FIG. 6 is a perspective view thereof, in a closed position.

FIG. 1

FIG. 2

FIG. 3

FIG. 4

FIG. 5

FIG. 6
